J. E. JONES.
SASH OPERATING DEVICE.
APPLICATION FILED MAR. 23, 1914.

1,109,928.

Patented Sept. 8, 1914.

UNITED STATES PATENT OFFICE.

JAMES E. JONES, OF RICHMOND, INDIANA.

SASH-OPERATING DEVICE.

1,109,928.

Specification of Letters Patent. Patented Sept. 8, 1914.

Application filed March 23, 1914. Serial No. 826,467.

To all whom it may concern:

Be it known that I, JAMES E. JONES, a citizen of the United States, residing in the city of Richmond, in the county of Wayne 5 and State of Indiana, have invented a new and useful Construction in Sash-Operating Devices, of which the following is a full, clear, and comprehensive specification and exposition, being such as will enable others 10 to make and use the same with exactitude.

The object of my present invention, broadly speaking, is the provision of a sash operating device for windows, or the like, being intended, primarily, to be employed in 15 connection with windows of commercial buildings, such as factories, greenhouses, and the like, wherein a group or a plurality of windows are to be operated synchronously from a single source of power applied at 20 one point. And, more specifically stated, my object is to provide a sash operating device which will be strong and durable in construction, positive in action, neat and compact in construction, easily operated and 25 controlled, and which can be manufactured and sold at a comparatively low price.

Other specific and minor objects of this invention will be brought out and made plain in the course of the following description 30 when taken in connection with the drawings forming a part of this specification.

The preferred mode of carrying out my invention in a practical manner, is shown in the accompanying drawings, in which—

35 Figure 1 is a side elevation of my invention, showing the same in operative position retaining a window-sash in open position. Fig. 2 is the same as Fig. 1 except that the device has been operated to close the sash, 40 and showing the sash in closed position. Fig. 3 is an enlarged detail view showing a vertical or cross section of the main portion of my invention. Fig. 4 is a perspective detail view of the spool alone. Fig. 5 is a perspective view of the block and stirrup. And 45 Fig. 6 is an edge view of the stirrup, block, and spool united.

Similar indices denote like parts throughout the several views.

50 In order that the construction, the operation, and the advantages of my invention may be better understood and appreciated I will now take up a detailed description thereof, in which I will set forth the invention as comprehensively as I may.

For the purpose of making clear the op-

eration and the advantages of my invention I have shown a window-frame in dotted lines, wherein the sides thereof are denoted by letter A; the sill being denoted by a; 60 the table being denoted by a', and the top of the frame being denoted by a''.

Letter B denotes the sash, in which is secured the transparency or glass C. The sash is fitted in the frame and it is supported by 65 two pivots D, whereby the sash may be turned horizontally as indicated. Secured to the inner wall of the building, or to the frame of the window, are a plurality of brackets, or hangers, as for instance the 70 bracket E, which are adapted to carry revolvably the shaft or pipe F, the same being located inward and above the lower edge of the sash, substantially as indicated. Secured to the inner face of the lower part of 75 the sash B is the clip 1, in which is pivoted, for vertical movements, one end of the rack-arm 2, which latter is adapted to extend inward, and above the shaft F. Secured on the shaft F, in alinement with the rack-arm 80 2, is the spool. The said spool consists of the body portion 3 which neatly surrounds the shaft F and to which it is detachably secured by the set-screw 4.

Formed integral with one end of the body 85 3 is the inner radial flange 5; and corresponding therewith and spaced laterally therefrom is the outer radial flange 6, the two flanges being integrally connected together by the bars 7, which latter are spaced 90 apart and they extend in an axial direction, thereby forming apertures to receive the teeth of the rack-bar as shown in Fig. 3. The said bars collectively form a pinion, the periphery of which does not extend out to 95 the peripheries of the flanges 5 and 6, that is to say, the diameter of the pinion is less than is the diameter of the flanges whereby a channel is formed between the flanges and the bars, in which may operate the stirrup 100 8. The stirrup is of a width to fit between the said flanges and it is adapted to cover one-half, approximately, of the periphery of the pinion, with the ends of the stirrup turned outward horizontally forming the 105 ears 8' and 8''. The said stirrup is formed, preferably, of sheet metal, with the said ears integral therewith. The block is also formed, preferably, of sheet metal, and it consists of an integral sheet cut into and 110 formed substantially as shown, and it comprises the two spaced apart triangular

shaped sides 9 and 9'. The lower edges of the said sides are formed concave, as at α in Fig. 5, to fit on the periphery of the pinion, that is on the bars 7, with which it may contact. The lower corner portions of the sides 9 and 9', on each side of the concaves α , are connected by the webs 9'' and 9'''. Extending out horizontally from the webs are the tongues 9^a and 9^b, respectively, which are adapted to contact with the respective ears 8' and 8'' of the stirrup, and they are adapted to be secured thereto by the respective rivets 10 and 10', substantially as shown. Extending across through the upper portion of the sides 9 and 9', and secured thereto, is the pivot 11. Located between the sides 9 and 9' and revolvably mounted on the pivot 11 is the roller 12.

Modus operandi: By means of the arrangement shown it is apparent that the arm 2 is slidably mounted in the block, with its upper edge in contact with the roller 12, and with the teeth of said arm meshing in the pinion as shown in Fig. 3. The stirrup 8 after being secured to the block retains the rack-arm in its operative position with relation to the pinion, substantially as indicated. Now suppose the device be assembled as in Fig. 2, it is apparent that if the shaft F be rotated to the left, by means immaterial to state in this application, then the pinion will operate upon the teeth of the arm 2 causing the said arm to move outward endwise to the position shown in Fig. 1, or to any intermediate point, or to any point therebeyond depending only on the length of the arm 2. As the arm 2 is connected to the window sash it is of course apparent that the window sash will be operated by the movements of the said arm. It is also apparent that any number of windows may be likewise connected to the shaft F and that all will be operated at one time as set forth. Also if the

shaft F be locked or held at any point it will lock all of the windows thereto attached, and will retain them securely in that position.

It is to be understood that my invention is not to be limited to vertical windows, as it will be equally applicable to roof windows such as are used in greenhouses, and it may also be used in connection with various other kinds of openings. It is also to be understood that various changes may be made in the several details of construction without departing from the spirit of my invention and without sacrificing any of the advantages thereof.

Having now fully shown and described my invention, what I claim and desire to secure by Letters Patent of the United States, is—

In combination with a rotary shaft and a window-sash adapted to be opened and closed; a spool secured on the shaft and comprising a body, an inner flange adjoining one end of the body, an outer flange spaced from the inner flange, bars connecting the two flanges and forming a pinion, the periphery of the pinion being of less diameter than the diameter of said flanges; a block resting on the periphery of said bars, a roller carried by the block, a rack-bar adapted to operate through the block contacting with said roller and engaging with said bars, and a stirrup engaging with the peripheries of the block and retaining the block in operative position, all substantially as set forth.

In testimony whereof I have hereunto subscribed my name to this specification in the presence of two subscribing witnesses.

JAMES E. JONES.
